UNITED STATES PATENT OFFICE.

WILLIAM SELLERS, OF PHILADELPHIA, PENNSYLVANIA.

IMPROVEMENT IN BORING-MILLS FOR METAL.

Specification forming part of Letters Patent No. 36,112, dated August 5, 1862.

To all whom it may concern:

Be it known that I, WILLIAM SELLERS, of the city of Philadelphia and State of Pennsylvania, have invented certain new and useful Improvements in Boring-Mills for Metal; and I do hereby declare the following to be a full and exact description of the same, reference being had to the accompanying drawing, and to the figures and letters of reference marked thereon.

My invention relates to the class of boring-mills for metal in which the piece to be bored revolves with a circular table or face-plate upon a vertical axis, and in which a vertical movement of the boring-bar in the line of said axis feeds the cutter through the work to be bored.

In the ordinary construction of boring-mills of this class the boring-bar is attached to a vertical slide suspended above the center of table and carried either by an arched frame the bases of which are attached at opposite sides to the bed of the machine, or by a horizontal cross-head attached to uprights also fastened to opposite sides of the bed; or the boring-bar and its slide are sometimes carried upon a stout semi-arched frame attached to one side of the bed only, its top inclining toward the center of rotation and embracing the slide in proper position to bring the axis of the boring-bar in line with the axis of the table.

It will at once be apparent that with any of the above constructions of boring-machines the diameter of the piece that will swing in the machine is limited by the frame-work attached to the bed and extending above the table to carry the boring-bar, and it will also be seen that the construction of a machine of the above description to swing large diameters involves great weight of the various parts to give the stability required for the proper action of the cutting-bar, although the character of the work to be done and the power consumed to do it may be comparatively light.

In order to diminish the weight of material and cost of the above-described machines, some boring-mills have been made in which the boring-bar is held by a spindle sliding in and supported by the spindle which carries the face-plate upon which the work to be bored

is bolted. The boring-spindle, having only a motion in the direction of its axis, and being held laterally by a revolving support, is peculiarly liable to wear, and as in this arrangement no provision has been made for the escape of the chips from the cutter, and the sliding spindle carrying the boring-bar must necessarily be surrounded by them, no nicety of fit is admissible or can be maintained, and the work performed by such a tool is necessarily of inferior quality as well as quantity.

Now, the main object of my invention is to construct a machine that will combine almost unlimited capacity for work of any ordinary character with perfect stiffness and with no more than usual liability to the wear of working parts.

To this end I dispense with all the frame-work above the table for carrying the boring-bar, and provide in the interior of the bed of the machine a strong vertical slide working in suitable bearings cast in the bed. This slide is, on its top, arranged to receive the cutter-bar, and provided with a rack, by means of which the vertical movement required for the action of the boring-bar is given, as hereinafter fully described. The rotating motion is given to the table by means of a bevel-pinion upon a horizontal shaft, gearing with teeth on the under side of the table. A long bearing is provided in the bed for the pinion-shaft, at the outside end of which is the driving-pulley, the upper half of this pulley being the only part of the machine that projects above the face of the table. The pulley is, however, so far removed from the center of the table as to form no impediment to the swinging of work of considerable diameter, and when pieces of uncommonly large diameters are required to be bored it is only necessary to provide an extension of the pinion-shaft with an outside bearing and to remove the driving-pulley as far from the center of the machine as is needed for the purpose.

It will be evident that with the above arrangement of the slide and boring-bar a central spindle with a step-bearing for the table is inadmissible. I therefore provide the table on its under side with an annular projection of considerable diameter and depth, which is fitted into a deep circular channel of corre-

sponding shape and diameter in the top of the bed. In this manner the table has not only a good bearing in the bottom of this circular channel, but it is also accurately guided between the sides of the said channel.

To insure continued efficiency of this arrangement a means of taking up the wear of these parts must be provided, and a peculiarly arranged and very effective device for this purpose, hereinafter fully described, forms another feature of my invention.

In order that my said invention and the manner in which the same is carried into practice may be fully understood, I will now proceed more particularly to describe the same, reference being had to the accompanying drawing, making part of this specification, in which the same letters of reference allude to similar parts throughout the several views, and in which—

Figure 1 is a sectional side elevation of my improved boring-mill. Fig. 2 is a sectional elevation at right angles to Fig. 1. Fig. 3 is a plan of the machine; and Figs. 4 and 5 are detached views of the device for taking up play in the circular groove in the top of the bed.

A is the bed of the machine. It is of a hollow cylindrical form, spread into a wide flange, a, on the bottom, and is, at the top, provided with a heavy rim, b, swelled outward from the cylindrical body of the bed. The top side of this rim or swell b is hollowed out to form a deep circular channel with slightly-beveled sides.

The table B is, upon its lower side, provided with two circular projections, C and D, the inner one of which corresponds in diameter and thickness with the channel in the top of the bed, and is accurately fitted to the sides of the said channel in which the table is thus guided in its rotating motion. This motion is given to the table by means of a bevel-pinion, E, gearing with teeth of corresponding bevel on the bottom of the outer circular projection, D, of the table. This pinion E is attached to a shaft, F, which has a long bearing in a sleeve, G, cast with the bed, to the body of which it is connected by means of a web, c, and rib c'.

The shaft F has upon its outer end a conical driving-pulley, H, for adjusting the speed of the machine to suit different sizes of cutters.

I is the vertical slide in the interior of the bed A. It has beveled sides o o, which are accurately fitted to vertical grooves of corresponding shape in the bed, the slide being confined between the said grooves in such a manner as to permit a vertical movement only, without sideward play in any direction.

The boring-bar K is attached to the top of slide I in the manner best seen at Fig. 2. It is screwed into the slide against a hexagonal collar, g, the lower end of the portion entering the slide being provided with a right-hand

screw-thread, so that the direction of the cut and the torsional strain upon the bar from the cut tends to screw it tighter into its socket.

In the annexed drawing, the slide I is represented as being actuated by means of a hand-wheel, L, and pinion M upon a shaft, N, the pinion gearing with a rack, h, in the slide. It will, however, be understood by any good mechanic that a combination of gearing may be substituted by means of which a self-acting feeding movement of the slide can be produced.

The arrangement of the parts for taking up any wear between the surfaces of the beveled circular projection C of the table and the sides of the channel in the top of the bed is as follows: The rim C is, on its lower side, hollowed out to form a deep narrow gutter with parallel sides, into which is fitted a T-shaped ring, P, in the manner seen at Figs. 1 and 2. The upper narrow face, d, of ring P is so shaped as to present a series of inclined planes, all running in the same direction, and of which there are three represented in the drawing. (See Fig. 4.)

The bottom surface, e, of the gutter C is shaped to coincide with the inclined planes on the ring P. This ring being placed in its position in the top of the bed, with the table B resting upon the inclined planes d d of the ring P, it will be evident that a variation in the relative position of the table B and ring P around their axis will, by the action of the inclined planes d and e, elevate or depress the the table, according to the direction in which either is moved, and thus provide an accurate adjustment of the sides of C to the beveled sides of the channel in the top of the bed. One of the inclined planes d on the ring P has teeth cut upon it, into which gears a pinion, k, on a small shaft, l. This has its bearing in the table B, and is at its outer-end provided with a squared projection for the application of a wrench to actuate the pinion whenever it is required to adjust the bearing-surfaces of C in the circular channel of the bed.

m is a set-screw, which, when tightened against the shaft l, serves to lock the pinion k and ring P, after the latter has been properly adjusted.

The depth of the gutter in C is, in relation to the whole height of the ring P, so proportioned as to leave some space between the lower surface of C and the bottom flange of ring P, so as to prevent any contact of the lower surfaces from interfering with the vertical adjustment of the table.

Having thus described the nature of my invention, I wish to be understood as not desiring to confine myself to the described construction and arrangement of the various parts in every minutia, as the same may be modified without thereby impairing my invention; but

What I claim, and desire to secure by Letters Patent, is—

1. The described construction of a boring-

hill for metal, in which the boring-bar is actuated and held in position laterally by a vertical slide placed beneath the table or face-plate of the machine, the whole being constructed and operating substantially in the manner and for the purpose specified.

2. The employment, in combination with

the table B, of a ring, P, or its equivalent when arranged and operating substantially in the manner and for the purpose set forth.
